Primary Examiner — Anhdao Doan(74) *Attorney, Agent, or Firm* — Caldwell Intellectual Property Law; Katherine Rubino(57) **CLAIM**

What is claimed is the ornamental design for a monitoring garment, as shown and described.

DESCRIPTION

FIG. 1 is a back perspective view of a monitoring garment;
 FIG. 2 is a back view thereof;
 FIG. 3 is a front view thereof;
 FIG. 4 is a right side view thereof;
 FIG. 5 is a left side view thereof;
 FIG. 6 is a bottom view thereof;
 FIG. 7 is a top view thereof;
 FIG. 8 is an environmental front view thereof attached to a brassiere;
 FIG. 9 is an environmental front view thereof attached to a shirt; and,
 FIG. 10 is an environmental back view thereof attached to a brassiere.

The broken lines represent environmental subject matter and form no part of the claimed design.

1 Claim, 8 Drawing Sheets(56)
